METHOD AND MEANS FOR PRODUCING
STOCKING WELT CONSTRUCTION

Otto F. Smetana, Concord, N. C.

Application September 19, 1942, Serial No. 458,982

17 Claims. (Cl. 66—96)

This invention relates to the knitting of full-fashioned stockings and more particularly to a novel method and means for forming the stocking welt.

When the knitting of a full-fashioned stocking is begun an initial loose course is usually formed by the knitting needles upon the hooks of a transfer bar, after which additional courses are added to the loose course until a welt fabric of the desired length has been formed. Then the initial course and transfer bar are returned to the knitting needles where the initial course is interknit with the fabric, thus forming a welt of a double thickness. In order to properly transfer the loops of the initial course to the needles, considerable skill and experience are necessary, because the loops of the initial course must be matched with the loops upon the needles and then the transfer bar must be manipulated successively into several positions so that the welt hooks can be removed when the course has been transferred. This operation involves much labor, loss of production and frequently is the source of many defects in the finished stocking.

It is an object of this invention to provide a welt transfer bar which simplifies the transfer operation to such an extent that highly skilled labor is not necessary to accomplish the same.

It is another object of this invention to provide a welt transfer bar which has means for expanding or distending the loops of the initial course during a transfer operation a sufficient amount to permit the open welt hooks to pass through the loops after the transfer to the needles has been effected, thereby permitting the welt bar to be removed from the fabric.

It is another object of this invention to provide a welt transfer bar having alternate long and short hook members for engaging the loops of the initial welt courses. The difference in the length of the long and short hook members should be at least as great as the distance between the first two of the initial courses of the stocking welt. This difference in length permits both the long and short hooks to receive the initial welt course and only the long hooks to receive the second course. For example, when attaching the initial courses of a stocking on the long and short welt hooks, all of the hooks are inserted horizontally between the vertically disposed needles to a point beyond the first course, which course is initially supported by the nibs of the sinkers and dividers thereabove. As the needle hooks are lowered and as the sinkers and dividers are retracted, the needle hooks engage the above-mentioned first

course and draw it downwardly upon the shanks of the welt hooks. Since the hooks of both the long and short welt members have been moved inwardly beyond the first course, it is evident that the welt bar cannot be withdrawn horizontally without all of the hooks engaging the first course. When the first course has been engaged, the machine is stopped to permit the take-up straps to be attached to the welt bar. The horizontal pull of the attached straps will cause the welt bar to move horizontally away from the needles a distance equal to the space between the first and second course, thereby completely withdrawing the short hooks from between the needles while the ends of the alternate long welt hooks still remain between the needles and in position for receiving the second course. The machine is again started and the second course is initially deposited upon the nibs of the dividers and sinkers, after which the needle hooks are lowered and the sinkers and dividers retracted as in the first course, thereby depositing alternate loops of the second course only upon the long welt hooks members alongside the loops deposited during the first course. The remaining loops of the second course will be knitted when the needles are lowered because the short hooks have been withdrawn from between the needle hooks when the take-up straps were applied. The attachment of the initial courses obviously involves a certain amount of manual operation; however, the manual operation is simple and easily accomplished. Therefore, when the two initial courses are returned to the needles, the two loops held by each long hook will be inter-knitted with a course in the stocking leg, and the single loop held by each short hook will be inter-knitted with the same course. Such a construction provides a lock stitch at the junction point of the above-described initial welt courses with the stocking leg. This lock stitch prevents runs which start in the welt from passing into the stocking leg.

It is still another object of this invention to provide an improved full-fashioned hosiery welt having the aforementioned lock stitch construction which prevents dropped stitches in the welt from running into the stocking leg.

It is another object of this invention to provide a welt bar comprising a plurality of hook members having loop expanding elements associated therewith, the loop expanding elements on alternate hook members being staggered with relation to the loop expanding elements on the remaining hook members. By staggering the expanding elements, only a portion of the loops in the initial

course or courses will be simultaneously expanded, thereby permitting slack to be borrowed from the adjacent loops. When the initial course or courses have passed over the first set of expanding elements they ride upon the expanding elements or the remaining elements, at which time slack is borrowed from the previously expanded adjacent loops.

An additional advantage, in providing alternate hooks of a greater length than the remaining hooks, is gained when returning the initial course to the needles. Alternate long and short hooked elements facilitates placing the bar in the proper relationship to the sinkers and knock-over bits because the alternate long hooks serve as leads or guides when the initial course is returned. At the same time, the two initial courses are held in a stable position on the welt bar to permit the transfer of only a portion of the loops at one time to the knitting needles.

It is still another object of this invention to provide a welt bar of the class described which is semi-automatic in operation. As a general rule, full-fashioned hosiery machines comprise a plurality of stocking units which are simultaneously operated from a common source of power, and therefore, an individual welt bar accompanies each unit. The present improved welt bar is of such a construction that the bar of each unit may be manually returned to the needles while the machine is not in motion, and then when the machine is placed in motion, the transfer of all the welts will be effected simultaneously. In other words, after all of the welt bars of the machine have been singly returned to the needles of the respective units, the transfer of all the welts on the machine are made together. Then the machine is stopped and the welt bars are removed, after which the machine is started and knitting of the shadow welt or leg proceeds. The present invention therefore makes it possible to simultaneously close the welts of all the stocking blanks on the respective units by the operation of the machine after all of the welt bars and initial courses have been positioned upon the needles. The returned welt bars are supported by the needles, which needles fit in longitudinal slots disposed in each welt hook.

Some of the objects of the invention having been stated, other objects will appear as the description proceeds when taken in connection with the accompanying drawings in which:

Figure 1 is a plan view of one unit of a flat or full-fashioned knitting machine showing one form of my improved welt turning implement associated therewith;

Figure 2 is a transverse vertical sectional view taken along the line 2—2 in Figure 1;

Figure 3 is an enlarged sectional view similar to the left-hand portion of Figure 2 illustrating the welt bar or implement in bold line position after a portion of the welt has been knitted, and also illustrating the welt bar or implement in dotted line position when the initial course or courses are being returned to the knitting needles;

Figure 4 is an enlarged plan view showing the position of the fabric between the knitting needles and the welt bar after the second course has been knitted;

Figure 5 is a plan view taken along the lines 5—5 in Figure 3 illustrating alternately spaced long points supporting alternate loops of the initial welt course while shorter hooks support the remaining loops;

Figure 6 is a sectional view taken along the line 75

6—6 in Figure 5, illustrating the structure of one of the long points in association with the initial welt course;

Figure 7 is an elevation similar to the central portion of Figure 3 showing the relative positions of the welt hooks and points;

Figure 8 is a view similar to the left-hand portion of Figure 3 but showing the process of expanding the loops of the initial course during a transfer operation to thereby permit the open welt hooks to pass upwardly through these loops while the welt bar is being removed;

Figure 9 is an isometric view illustrating the positions of the welt hooks, alternately spaced long points, sinkers, dividers, together with the two layers of welt fabric during the returning of the initial course to the needles;

Figure 10 is a view similar to Figure 9 but showing the reverse sides of the welt hooks, points, and knitting needles, and omitting the fabric therefrom;

Figure 11 is an isometric view similar to Figure 9, illustrating the position of the welt implement as it appears when first positioned between the knock-over bits and upon the needles;

Figure 12 is an enlarged view similar to Figure 3 but showing a slightly modified form of welt bar in association with the sinkers and knock-over bits while the initial course is being knitted;

Figure 13 is a view similar to Figure 12 but showing the position of the welt bar or implement after the welt has been knitted and while the initial loose course is being returned to the knitting needles;

Figure 14 is a plan view taken along line 14—14 in Figure 13;

Figure 15 is a view similar to Figure 13 but showing the next step after the initial course has been returned and knitted to the welt fabric, namely 40 the expansion of the loops of the returned course to permit the welt hook to pass therethrough without engaging the same;

Figure 16 is an isometric view of the welt hooks associated with the bar shown in Figure 14, said view illustrating a staggered relationship of the loop expanding means;

Figure 17 is an enlarged view similar to Figure 3 but showing another modified form of welt bar or implement as the same appears when returning the initial loose course to the knitting needles;

Figure 18 is an isometric view illustrating the welt bar and associated welt fabric when the same are returned to bold line position as shown in Figure 17;

Figure 19 is an isometric view showing the opposite sides of a welt hook and point from the side shown in Figure 18, said view exposing the bearded sides of the knitting needle and welt hook;

Figure 20 is a sectional plan view taken along the line 20—20 in Figure 17;

Figure 21 is a sectional plan view taken along the line 21—21 in Figure 17;

Figure 22 is a vertical sectional view similar to Figure 3 showing still another modified form of the welt bar in which each welt hook has a slot extending therethrough for the reception of a knitting needle during the transfer of the initial welt courses to the needles;

Figure 23 is an enlarged view similar to the central portion of Figure 22 but showing the welt bar elevated to a slightly higher position;

Figure 24 is an isometric view of a portion of the welt bar shown in Figure 22;

Figure 25 is an isometric view of still another

modified form of welt bar in which alternately spaced long and short hooks are employed, but omitting the loop expanding means therefrom;

Figure 26 is an elevation of a stocking having a welt formed by use of my improved welt bar;

Figure 27 is a sectional view through the welt of the stocking;

Figure 28 is an enlarged detail view illustrating the lock stitch junction at the point where the initial welt course is returned to the leg of the stocking;

Figure 29 is an isometric view further illustrating the lock stitch junction where the initial course is returned to the leg of the stocking.

Referring more particularly to the drawings, the numeral 10 denotes an end frame of a full-fashioned knitting machine, said frame being adapted to support longitudinally disposed rail 11, table member 12, and take-up roll shaft 14. The rail 11 supports top and bottom sinker beds 15 and 16 respectively, which beds slidably confine spaced sinkers 17 and alternately spaced dividers 18 therebetween. (See Figures 8 and 9.) Rail 11 also supports in a conventional manner plate member 20, which, in turn, supports spaced knock-over bits 21, there being a knock-over bit for each sinker and also a knock-over bit for each divider. (Figures 8 and 11.)

A bearded knitting needle 23 is mounted for vertical movement in each space between the sinkers 17 and the dividers 18. The lower ends of these needles are attached to a bar 24, (Figure 1) which is operated in a conventional manner by a conventional mechanism, not shown.

During the knitting of a stocking, one or more yarn carriers 25 are moved back and forth longitudinally of the sinker bed plate 15 to thereby feed a strand or strands 26 to the bearded hooks of needles 23. (Figures 1 and 2.) When the strand 26 has been deposited on top of the sinkers and below the beards of the needles 23, the needles are then lowered to knit the strands. The sinkers 17 and dividers 18 move horizontally back and forth in timed relation to the vertical movement of the needles 23 to cause the loops to be shed and thus clear the beards of the needles 23 so that a successive course can be knitted.

When a stocking is begun, it is general practice to first knit a loose course and attach the same to the hooks of a welt bar such as 27. This process of attachment may be effected in many ways, however, it is well to state that it can be accomplished by first feeding a strand 26 beneath the beards of the raised needles and on top of the extended sinkers to form the first welt course. Then, with the needles partially down between the sinkers 17 and dividers 18 and with the stitches hanging over the nibs of the sinkers and dividers, the welt hooks are inserted in the first course beneath the sinkers and dividers, after which the knitting needles 23 are completely lowered simultaneously with the retraction of the sinkers and the dividers to release the sinker loops of the first course upon the welt bar hooks. This first course is then attached onto the hooks of the welt bar 27. Then it is only necessary to pull the welt bar horizontally away from needles 23 and attach it to suitable welt straps 29, which straps apply a constant tension to the fabric while successive courses are being knitted. (See Figures 1 and 2.) The other end of straps 29 are secured to a conventional take-up roll 30 which is secured upon the shaft 14 previously described.

As a means for supporting the ends of the welt implement 27, suitable guides 31 are secured as at 32 to the table member 12. The pull which is normally exerted by the take-up roll 30 maintains a tension in the straps 29 and in the knitted fabric which is disposed between the welt hooks and the knitting needles. This tension also serves to hold the ends of the welt bar or implement 27 upon the spaced parallel guides 31 and thus causes the welt bar to follow a defined path.

The structure thus far described is conventional in full-fashioned hosiery machines, but it is thought that this much of the conventional mechanism should be described to more fully disclose the advantages of the present invention.

Figures 3 to 9 inclusive illustrate one form of my improved welt bar or implement and the method employed of forming a welt when using the same. This welt bar 27 has a plurality of spaced parallel short and long hook elements 33 and 34 respectively extending from one edge thereof. Each of the hook elements 33 has a reversely bent hook 35 upon one end thereof which is employed for engaging and holding alternate sinker loops of the initial or setting up course 36 in a stocking welt.

In the present disclosure the end of each hook has a ball point 37 integral therewith and this point serves as a yarn guide when attaching or removing the initial course to or from the welt bar.

Adjacent each hook 35 and on the same side of the welt bar are a pair of cam projections 38, which are substantially higher than the hook portions 35. These projections are employed for expanding the above-mentioned alternate loops of the initial course 36 when a transfer is being made. (See Figures 3 and 7.) The long hooks 34 have similar cam projections 42 integral therewith and disposed adjacent the point where its loop is held. These projections 42, however, are staggered with relation to projections 38 on the adjacent needles so that during transfer only alternate loops in the initial courses will be disposed upon the cam projections at a time. The function of these projections during a transfer operation will be later described.

On the back of each hook element 33 is a longitudinal groove or slot 39 which is employed for receiving the spring beard 23a of knitting needle 23 when a transfer is being made, that is, when the welt bar and associated needles and points are moved to the position shown in Figures 3 and 8. Likewise the alternate long hook members 34 have a longitudinal groove 40 in the back side thereof which has the same function, namely the function of receiving one of the spring beards 23a of its associated needles during a transfer operation.

It will be noted that the ends of long hooks 34 extend a substantial distance beyond the ends of short hooks 33 (Figures 3 to 10 inclusive.)

Also there is a slight variation in the structure of the long hook from that of the short hook. Instead of having a long beard or hook 35, the end of the long hook 34 has an upstanding projection or ball 41 integral therewith which ball serves as a hook for holding alternate loops of the initial courses. In order to effectively operate this bar, it is desirable to locate projection 41 a walewise distance beyond the end of short hook 33, and this distance should be at least equal to the distance between the first two courses. This distance permits all of the hook members 33 and

34 to engage the first course 36 and only the long hook members 34 to engage the loops of the next succeeding course. More specifically, when attaching the first two courses to the welt hooks, it is first necessary to insert welt members 33 and 34 horizontally between needles 23 and upon knock-over bits 21 until the ball 37 of member 33 is disposed to the left of needle beard 23a (Figure 3). It is of course understood that the needles will be raised and that the nibs of the sinkers 17 and dividers 18 will be projected to the right from the positions shown. The thread guide 25 will then deposit the initial course upon the nibs or ends of the sinkers and dividers, after which the needles 23 will be lowered to cause the beards 23a to engage the deposited first course. As the needles continue to lower, the sinkers and dividers are simultaneously retracted to the position shown in Figure 3, thus releasing the first course and permitting it to be deposited upon the shanks of the long and short welt members 33 and 34. At this time, the machine is stopped to permit the take-up straps 29 to be attached to the welt bar 27. The tension exerted by the straps will withdraw the horizontal welt bar to the right a sufficient distance to cause the left-hand end of hook 35, as viewed in Figure 7, to be disposed to the right of needle 23 (Figure 3), and to cause the hook or ball portion 41 to be disposed to the left of needle beard 23a. The machine is again started to cause the needles to rise and the sinkers and dividers to be moved outwardly to the right of the position shown in Figure 3. Then the second course is fed to the needles in a similar manner as described regarding the first course, but due to the change of position of the welt bar as a result of the take-up straps, the second course will be engaged only by the long welt members 34, since the short members have been moved horizontally out of the downward path of travel of the needles 23; consequently, the loops of the second course between the long hook members will be knitted into a fabric. When these initial courses are returned to the needles 23 to form a welt, an anti-run barrier will be set up at the junction line of the initial courses with the leg of the stocking, which barrier will prevent welt runs from extending into the leg portion of the stocking.

It is seen in Figures 3, 4, and 5 that the projecting ends of the long hooks 34 serve to support the alternate loops of the loose course 36 and thus permit these alternate loops to creep farther to the left than the remaining loops which are engaged by the hooks 35. In other words, the alternate loops are supported by the long hooks but are allowed to slide longitudinally to produce a greater slack in the loops engaged by the hooks 35. This is a very important part of the invention because one of the principal advantages in providing a welt bar 27 of this type is in having means for distending the alternate loops held by the hooks 35 during a transfer operation to thereby permit the bar to be removed from the fabric in a rectilinear path during transfer without allowing the open hooks to engage the loops.

In Figures 3 and 7 the relative positions of the long and short hooks are shown. The end of long hook 34 is bent upwardly so that its associated short loop will be held slightly higher than the adjacent long loop disposed on hook 33. Since the long loop causes the short loop to be under considerable tension at all times, the short loop will thereby press downwardly against the upwardly bent end of the long hook 34, and conse-

quently, a very short ball 41 will effectively serve as a hook. Also by having the ball 41 serving as a hook, the engaged loops may be more easily transferred when the initial courses are returned to the needles.

In order to be more explicit, as to the function of the alternate long hooks and alternate short hooks, let us refer again to Figures 4 and 5. It is seen that the loose course 36 has a V-shaped kink of considerable depth as at 45 where the hooks 35 engage the same. The alternate loops, which are supported by the long hooks 34 do not have a sharp kink therein but are allowed to have substantially less bend where the loops cross over the tops of the hooks 34 as at 46.

There is another decided advantage in having alternately spaced long and short hooks, namely, the holding of the kinked loops 45 and 46 of the first course in a stable position when manipulating the welt bar. In other words, when raising the welt bar from horizontal position to an upright transfer position, (Figure 3) the first course 36 is not subject to rotation about the hooks because the loops 46 are engaged by hooks 41 along one line whereas the remaining loops 45 are engaged by hooks 35 which are located along another parallel line which is disposed a considerable distance to the right in Figure 4. This engagement of the loose course 36 along two separate parallel lines permits a better control of the fabric while manipulating the welt bar. If each loop 45 and 46 were engaged by aligned hook elements 35, then if the welt bar should be manipulated, the first course and attached fabric 35 would be free to rotate upon the hooks of the needles and hang in a substantially vertical position whenever the welt bar changed its elevation or position.

Each of the long hooks 34 has a knee portion 40 41 which is employed for limiting the uppermost position which the loops of the initial loose courses can occupy when a transfer is being effected. These knees also serve as a means for pushing fabric downwardly over the knitting needles and against bits 21 when the initial course or courses are being returned to the welt fabric. The function of these projections will become more apparent as the description proceeds.

After the initial courses have been attached to 50 the welt bar hooks in the manner shown in Figures 1, 2, 3, 4, and 5, and after a sufficient length of the welt has been knitted, a rod 48 is laid on top of the knitted welt, that is, in the dotted line position shown in Figure 3. Then the initial 55 courses, which are moved on the hooks 35 and 41, are slipped over the cam projections 38 and 42 and upon the shank of the hook elements 33 and 34 until the alternate loops engage the knee portions 47. At this time the hook elements 33 and 34 substantially occupy the dotted line position shown in Figure 3. In this dotted line position the grooves 39 and 40 in the backs of hook elements 33 and 34 respectively fit against the beards 23a of the needles 23. Figures 8 to 11 inclusive clearly show this transfer position. In Figure 11, the welt fabric is omitted for the sake of clearness. In other words, the position of the welt bar 27 in Figure 11 corresponds to the dotted line position of the bar in Figure 3.

When the bar is first returned to the needles, 70 it is necessary to properly position the same so that the loops of the initial courses will match the loops upon the needles 23. The elongated hooks 34, that is, that portion of each hook 34 which projects beyond the ends of hooks 35, serve

as a guide during the insertion of the points and hooks upon the needles. When the proper position of the long hooks has been attained, the intermediate hooks will also be in the proper positions above the corresponding needles 23. Then all of the hooks 33 and 34 are completely inserted to the lowermost position which is shown in dotted lines in Figure 3. In this dotted line position, the loose course will be disposed below the sinker and divider level.

With the returned bar in an inserted position, the machine is operated a sufficient amount to cause the needles 23, the associated hooks 34 and 35, to be simultaneously raised.

During the raising of the welt bar and needles 23, the sinkers 17 and dividers 18 will move forward to substantially the position shown in Figures 8 and 9, to prevent the returned loose course 36 from rising. Therefore, when the returned initial courses engage the bottom of the sinkers 17 and dividers 18, the hooks 33 and 34 will slide upwardly through the loops 45 and 46. When the cam surfaces 38 reach the loops 45 on the hook elements 33, the loops will be expanded sufficiently to provide ample clearance for the passage of open hooks 35, as these hooks and associated welt bar are moved upwardly. Of course, when the open hooks 35 pass through the expanded or distended loops on the loose courses, slack is borrowed from the adjacent loops 46, thus decreasing the size of this loop.

Immediately after the distended loops 45 pass over the balls 37 of hooks 35, the adjacent loops 46 begin to ride upon cam projections 42 of the adjacent hooks to thereby cause these loops 46 to be expanded. Since the loops 45, at this time, are off the cams 38, ample slack may be borrowed by loops 46 from loops 45 to permit the loops 46 to expand sufficiently when passing over cams 42. The function of cams 42 is similar to the function of cams 38, namely the expansion of loops 46 to permit the open hooked ends 41 to pass therethrough when making a transfer.

It is thus seen that by staggering the cam projections 38 and 42, and by providing long and short hooks, the loops on the short hooks are first transferred and the loops on the long hooks are next transferred. Such an arrangement makes it possible to effect a transfer with a minimum amount of slack in the first course. After the transfer has been completed, the bar 27 is removed, and then the straps 29 are hooked onto rod 48 so that continued knitting of the stocking leg can be effected.

It is seen in the drawings that there are two cam surfaces on the hook side of each hook element 33 and 34. If desired, a single cam surface of suitable height and shape may be provided, and essentially the same results can be obtained in the transfer operation described in connection with Figures 3 to 11 inclusive. The purpose of providing two surfaces in this first form of the invention is a matter of manufacture rather than the result obtained.

Although a partially closed spring hook is associated with each of the hook elements 33, the invention is not limited to hooks of this type. An open hook can be used with equally effective results provided the cam projections are of sufficient height and located sufficiently close to the hook to expand the initial loops during transfer so that the loops will not contract quickly enough to be caught by the hooks.

Figures 12 to 16 inclusive show a slightly modified form of welt implement and method of re-

turning the initial course of the welt to the needles. This welt turning implement is broadly designated by the reference character 49 and comprises a plurality of parallel spaced hook elements 50 and 51, together with alternately spaced U-shaped stop elements 52. Each of the hook elements 50 has a pair of cam surfaces 53 disposed near the left-hand end thereof in Figures 12 to 16. Adjacent the cam surfaces and upon the end of each needle is a spring hook 54, the end of said hook having a ball 55 thereon which is disposed in close proximity to the cam surfaces in practically a closed position. It will be noted that the hook 54 is bent upwardly so that its spring point will be directed toward the base of the cam surfaces 53.

The structure of alternate hook elements 50 is very similar to the structure of hook elements 51. Each element 50 has a pair of cam projections 56 on the hook side thereof but in a staggered relation to the projections 53 on elements 51. Also an upwardly bent spring hook 59 is disposed on the end of element 50, said hook having a ball 59a on its end which is normally disposed in close proximity to the base cam projections 53, and in practically a closed position. Since the elements 50 and 51 are not staggered, it is necessary to make the hook 59 considerably shorter than hook 54.

The intermediate or alternate stop members 52 are U-shaped as at 52a, said U-shaped portions being disposed in spaced relation to the opposite sides of cam surfaces 53 and 56 from the hooks 54 and 59. As in the preceding form of the invention the engaging of the initial courses by the hooks 54 and 59 of the welt members 51 and 50 involves a simple manual operation. When it is desired to use this form of welt implement, the closed upturned hook portions 54 and 59 are inserted beneath the press edge 16a of the sinker bed 16, and in substantially bold line position as shown in Figure 12. Then the implement is released and permitted to fall to dotted line position on top of knock-over bits 21. Since the hooks 54 and 59 are bent upwardly, this downward movement of the right-hand end of welt bar 49 in Figure 12 will cause the hooks 54 and 59 to be opened. The distance that the hooks 54 and 59 are inserted beneath the press edge varies, but it is evident that the press edge is employed to widen the throat opening of the welt hook to facilitate the entry of the first course of yarn. Then the initial course is fed over the nibs of the sinkers and dividers in a known manner such as shown in Figures 20 to 23 inclusive in the patent to Nebel No. 2,326,964. As in this patent, every other loop of the applicant's initial course is thrown off over the needle heads, owing to the provision of suitable conventional transfer needles (not shown) in the front of every other knitting needle 23. These transfer needles throw off every second loop prior to the pressing operation and by further known operations each loop of the first course is engaged by one short hook 59 and one long hook 54.

Upon the sinkers and dividers retracting fully between the members 15 and 16, the sinker loops of the first course will slide beneath the opened hooks 54 and 59, after which it is only necessary to attach the welt bar 49 to the tension straps 29 in the same manner as described in connection with welt bar 27. During the lowering of the needles 23 which draw the initial course against the tops of the welt hook shanks, the welt bar is manually withdrawn, but at the same time maintaining the left-hand ends of the hook mem-

bers (Figure 12) beneath the press edge until the initial course is disposed in both the long and short hooks. Figure 14 shows the welt hooks 54 and 59 engaging only the first course.

After a sufficient length of the welt has been knitted to the initial course 57, the loops of this course are then moved from beneath the hooks 54 and 59 and slipped over the cam surfaces 53 and 56 until the U-shaped stop members 52a are engaged. Figures 13 and 15 show the positions of this initial course as it is being returned to the needles 23. In other words, the welt bar 49 is returned to the needles and the hook elements 50 and 51 are inserted between needles 23 in the position shown in Figure 13 until the hooks 54 and 59 are disposed beneath the press edge 16a and until the U-shaped stop members 52a are disposed directly above the needles 23. It is, of course, necessary that the needles 23 be in the lowered dotted line position shown in Figure 13 when the initial course 57 and bar 49 are first returned to the needles. Then the knitting machine is manipulated to cause the needles 23 to be raised from dotted line position upwardly through the U-shaped members 52a and within the loops of the initial loose course 57. With the needles in a raised position, the next succeeding tie course 58 is formed by the needles, which course units the initial course again to the welt fabric, thereby closing the welt and providing a welt of double thickness.

At this time, the welt bar 49 is withdrawn from the position shown in Figure 13 to the position shown in Figure 15. It is seen that as the bar is withdrawn, the loops of the knitted initial course 57, as well as tie course 58, will be expanded at different times by the cam surfaces 53 and 56 sufficiently to permit the hook ends 54 and 59 to pass therethrough without engaging the same. The staggering of the cam surfaces permits the entire slack of the loop on hooks 54 and 59 to be utilized successively as the respective hook points 55 and 59a respectively are withdrawn to the right as shown in Figures 13 and 15. Although the spring hook ends 54 and 59 will substantially close after the same have been released from the press edge 16a, the expanded loops of the courses 57 and 58 will permit the hooks to pass therethrough without engaging the same even though the hooks should not be fully closed.

As in the first form of the invention, the cam projections 53 are staggered with relation to cam projections 56 so that only half of the loops in the junction courses will be expanded at a time. In other words, the loops on hooks 51 are first expanded by cam projections 53 and after passing over these projections, the loops on the remaining welt hooks 50 expanded by cam projections 56.

When the welt bar 49 is completely removed, the tension straps 29 are hooked onto a welt rod 48 such as shown in Figure 3 and the knitting of the stocking leg is continued in a conventional manner. It is seen that the cam surfaces 53 and 56 in this form of the invention likewise serve an important function which permits the welt bar to be easily removed from the fabric after returning the loops of the initial course, and without hanging any of the loops upon the hooks.

The bending up of the hooks 54 and 59 greatly reduces the likelihood of the hook points engaging the initial course when the bar is removed. Nevertheless, if it were not for the cam surfaces 53 and 56, the method of removing the bar in a

horizontal position without having a latch on the hook would be impractical.

Figures 17 to 21 inclusive show still another modified form of the invention which is similar to the form shown in Figures 3 to 10 inclusive except the transfer is made by positioning the bearded or hook side of each welt bar element against the back side of a knitting needle, instead of positioning the same against the front side. The welt turning implement or bar employed in effecting a transfer by this method is broadly designated by the reference character 60. It is seen that the bar 60 has a plurality of short parallel hook elements 61 extending from one edge thereof, each of said elements having a pair of spaced cam projections 62 integral therewith, thus providing a slot 63 therebetween.

Adjacent the cam surface 62 and in close proximity to the lower edge of slot 63 is a spring hook 64, said hook having a ball point 64a forming one side of the hook throat through which the yarn passes when attaching and transferring the same to and from the welt bar. Communicating with slot 63 and disposed on the same side of element 61 is a shallower slot or groove 63a, and this slot receives the back of the needle to serve as a guide when the bar is pushed farther down upon the needles than shown in Figure 17. Although a spring bearded hook is shown, it is to be understood that hooks having a rigid beard may be employed without departing from the spirit of the invention.

These hook elements 61 are alternately spaced with long hook elements 66, each of said elements 66 having a pair of spaced cam projections 67 on the left-hand side thereof thereby forming a slot 68 therebetween, and this slot 68 receives the back side of a needle 23 during the transfer.

Likewise in this form of the invention, the slot 68 between the two cam surfaces, has communicating therewith, a shallower groove or slot 69. This groove 69 is disposed upon the same side of the hook as the cam surfaces and serves to accommodate the back of the knitting needle 23 when the welt bar is moved downwardly upon the needles farther than shown in the drawings.

Attention is called to the fact that the cam surfaces 62 and 67 are staggered on their respective hook elements for substantially the same reason as in the preceding forms of the invention, namely that for permitting only a portion of the loops in the initial courses to be expanded at a time during the transfer.

For example, when the welt has been knitted of a sufficient length, and it is desired to return the initial courses to the needles, these initial courses are first slipped over the cam projections 62 and 67 and upon the shanks of the welt hook elements 61 and 66. In other words, the initial courses 36 and 36a of the welt fabric will occupy the positions upon the welt hooks 61 and 66 shown in Figures 17 and 18. Prior to transfer, these courses will be disposed against the lower sides of knee portions 72 which are formed upon alternate long hooks 66 at a predetermined distance above the cam surfaces. With the fabric and welt bar in the position shown in Figures 17 and 18, the knitting needles 23 are preferably in a lowered position where the upper ends thereof are substantially flush with the top of the bits 21. Also at this time, the portion of the fabric which is being knitted, namely course 36c, is disposed below the knock-over bits 21, and upon the shank of needles 23. The operation and mechanical manipulation necessary to position the body of the welt fabric

below the knock-over bits is conventional, and therefore, will not be described, however, it is to be understood that the knitting of the fabric usually takes place above the knock-over bits 21. Prior to the transfer, the needles 23 are so moved to cause the fabric engaged thereby to be lowered to the position shown in Figures 17 and 18.

With the parts in the position shown in Figure 17, the machine is manipulated so that the needles 23 and the associated welt bar 80 will move to the right a sufficient amount to clear the right-hand end of bits 21, and then upwardly for a distance equal to the height of the bits, and then again to the left so as to position the course 36a, which was formerly below the knock-over bits, above these same bits. The entire assembly is then moved vertically so that the initial courses will slide downwardly over the cam surfaces 62 and 67 and onto the shanks of knitting needles 23.

Figure 19 clearly shows the bearded side of the needles 23 and the position they occupy relative to the cam projections 62 and 67 during transfer. The purpose of these cam projections and the slots 63 and 68 is to shield the beards 23a of the needles so that when transfer is being effected the initial courses 36 and 36a can be properly applied to the needles. Of course, these cam projections also serve the function of expanding the loops in a manner previously described so that the hooks 64 and 73 will not engage the associated loops when the welt bar is being removed from the fabric after the transfer has been effected.

Likewise, in this case, the purpose of providing a very short hook 73 on the end of each alternate long element 66 is to facilitate the easy removal of its associated loop therefrom during transfer. Since the ends of alternate long elements 66 are bent up a slight amount above the hooks 64 of the remaining elements 61, the loop which is associated with the hook 73 is held very taut, and therefore, a long hook is not necessary. Furthermore, the wale-wise distance between the points where hooks 73 engage the loops and the points where hooks 64 engage the loop, is at least equal to the depth of a course and possibly more. Therefore, alternate long hook elements 66 will engage the loops of the first two courses 36 and 36a, whereas the short hook elements 61 will only engage the loops of the first course 36. It should be kept in mind, however, that the same principle is employed in this form of the invention as in the preceding forms, especially as to the method of expanding a portion of the initial course loops at a time during transfer, and also in providing alternate long and short welt hooks.

Figures 22, 23, and 24 show another modified form of the invention which is similar to the preceding forms in many respects. In this form, the welt bar is broadly designated by the reference character 75, which bar has a plurality of short welt hook elements 77 and long welt hook elements 78. The difference in length in these hooks should be at least the distance between the first two courses of the stocking welt, and possibly greater, for reasons previously described in connection with the other forms of the invention.

The structure of the welt hooks 77 and 78 is practically identical, each hook having a pair of spaced cam projections 79 on the lower end thereof adjacent a hook point 80, said projections being staggered one with the other. The purpose of these cam surfaces 79 is similar to that of the preceding form, namely the expansion of a portion of the loops of the first courses at a time during the transfer. Also each of the

hook elements 77 and 78 has a slot 82 extending therethrough at a point opposite the cam projections 79, and this slot is of the proper size to accommodate the upper end of a needle 23 in the manner shown in Figures 22 and 23. Communicating with each of the slots 82 is a groove 84 on the bearded or hooked side of the hook element. These grooves 84 accommodate the upper end of the needles when the welt bar is pushed downwardly slightly farther than shown in Figure 22 during a transfer.

Attention is called to the Figures 22 and 23. When the initial courses 36 and 36a are first re-tured to the needles 23, the hooks 80 on the short hook elements 77 are pressed against the outer free ends of the needle beards 23a and therefore the welt hooks are closed, whereas the hooks on the longer elements 78 are disposed slightly below and in spaced relation to the associated beards 23a in the manner shown in Figure 22. In other words, the free ends of hook portions 80 on short elements 77 are closed by the end of beards 23a when the transfer bar is first re-turned, and at the same time, both members 80 and 23a are disposed immediately below a cam projection 79, but the hook 80 on the long element is not closed at this time.

During transfer, the welt bar is first placed upon the needles in the position shown in Figure 22, and then when the needles 23 and associated welt bar 75 are raised, the welt bar is additionally moved upwardly relative to the needles 23 so that the hooks 80 on the long elements 78 will engage their associated beards 23a in the manner shown in Figure 23 to close hooks 80. During this relative upward movement of bar 75, the hooks 80 on the short element will ride farther upwardly upon their associated beards 23a in the manner shown in Figure 23. The associated cams 79 alternately expand the loops in the first courses and thus prevent these loops from entering hooks 80 as the bar is withdrawn. Therefore, it is seen that the principal difference between this form of the invention and the preceding form resides in the extension of slot 82 completely through each hook element whereby the hook portion 80 on the lower end of the element may be closed by the beard 23a of the knitting needles during transfer, and at the same time, be shielded from the loops by the cam surfaces 79.

As heretofore stated, the above-described welt bars are semi-automatically operated when the welt transfers are effected; that is, all of the bars 53 of the machine may be individually positioned upon the needles by the operator and then when the machine is started the closing welt courses of all the units will be simultaneously formed solely by mechanical means.

Figure 25 shows still another modified form of the invention which is identical to some of the preceding forms except certain portions thereof are omitted. This welt bar is broadly designated by the reference character 85 and has a plurality of spaced parallel long and short hook elements 86 and 87 respectively. Each of the needles 86 and 87 has a groove 88 in the back portion thereof, and a hook 89 on the lower end thereof. The wale-wise distance between the hooks 89 of the long and short elements is at least equal to the distance between the first and second courses of the stocking welt. In actual operation this bar differs from the conventional welt bar only in having long and short points 86 and 75 87 thereby providing means for holding the first

course on all of the hooks 89, and for holding the second course on every other hook. As previously stated, this arrangement permits a novel lock stitch to be formed at the welt junction, so that welt runs will not extend into the leg of the stocking.

Figures 26 to 29 inclusive show an improved stocking welt construction which is formed when employing the present invention. This welt is such that a lock stitch will be provided at the point where the initial courses are returned to the leg of the stocking, which stitch prevents welt runs from extending into the stocking leg. It is very often the case that the supporters of a stocking tear the stocking welt and thus produce a run which, in turn, extends throughout the stocking leg and renders the stocking unsightly and useless. This particular lock stitch will confine the run within the stocking welt and therefore, will do very little damage to the appearance of the stocking.

In order to better understand the present lock stitch junction between the initial courses of the welt, and the leg of the stocking, it will be better to again refer to the structure associated with Figures 3 to 9 inclusive. It has been fully described in the specification how the two initial courses of the stocking welt are attached to the long and short welt hook elements. Briefly, the short hook elements of the welt bar engage every loop of the first course, but do not engage any of the loops of the succeeding courses, whereas the long hook elements engage loops of the first and second courses. Of course, if the long hook elements were extended possibly the loops of the third course might be also attached upon the long hooks.

When the initial courses 36 and 36a, thus engaged by the welt bar hook elements, are returned to the fabric in a manner such as shown in Figure 9, the first and second course loops on the long hook elements are united with the corresponding loops of the course 36c on the needles, whereas only one course 36 on the short hook elements is united with this same course 36c.

Referring to Figures 26 to 29 inclusive, the numeral 90 designates a stocking having a double welt portion 91, a leg portion 92, and a foot portion 93. When the initial courses 36 and 36a of the welt are transferred from the welt hook elements to the stocking leg, these loops are interknitted with the course 36c by a course 36d. The intermediate courses 36b form the body of the double welt construction, whereas the courses 36, 36a, and 36c and 36d form the junction courses. These courses are broadly designated as junction A.

The loops of courses 36 and 36a are combined with loops 36c in wales 96 by the course 36d, but in the adjacent wales 97, only the loops of courses 36c, 36, 36a and 36d are combined. It is thus seen that of the two initial courses 36 and 36a, these courses are combined into a single course in the wales 96, whereas these same courses are permitted to remain as separate in wales 97. Such a structure as heretofore stated will prevent runs which occur in the welt from extending into the leg portion of the stocking.

Although in the drawings, I have shown a short hooked element alongside a longer hooked element and then repeated this arrangement throughout the length of the welt implement, and in the specification and the claims I have described this arrangement as being "alternate," it is desired to be understood that two or more

long hooked elements could be used alongside each other and then one or more short elements could be disposed adjacent this long hook element to accomplish substantially the same results.

5 Wherever in the specification and claims reference is made to the term "alternate," there is no intention thereby limiting the specification or claims to every other hooked element or to every other loop, but such a limitation is intended to cover as well structures or methods wherein one or more long hooked elements or loops are interspersed among short elements or loops in regular or irregular order.

In the drawings and specification there has been 10 set forth a preferred embodiment of the invention and although specific terms are employed, they are used in a generic and descriptive sense only and not for purposes of limitation, the scope of the invention being set forth in the appended claims.

I claim:

1. A welt transfer bar for flat full-fashioned knitting machines, said machines having bearded needles, sinkers and knock-over bits for cooperating with said bar during the knitting of a stocking welt, comprising a plurality of elongated hook elements for engaging alternate loops of the initial course of the welt, a plurality of shorter hook elements for supporting the remaining loops of the initial welt course, a transversely disposed member uniting one end of said elements, and means associated with some of said elements for holding the elements in position upon said needles during a transfer.

2. A welt transfer bar for flat full-fashioned knitting machines, said machines having bearded needles, sinkers and knock-over bits for cooperating with said bar during the knitting of a stocking welt, comprising a plurality of short hook elements for engaging alternate loops of the initial course when knitting the welt, a plurality of alternately spaced long hook elements for supporting the remaining loops of the initial welt course, a transversely disposed member uniting one end of said elements,

45 each of said long and short elements having a shank portion for supporting the initial course loops during a transfer, said shank having a longitudinal groove in the back side thereof and also having a loop expander on the front side thereof adjacent the throat of the hook element, said groove being adapted to accommodate a needle beard when the bar is moved to transfer position upon the needles, wherein the initial course loops are disposed upon said shank portions above the loop expander and below the sinker level, whereby the initial course loops will slide over the expanders upon the upward movement of said needles and bar and thereby be expanded by said expanders sufficiently to permit the passage of the adjacent hooks therethrough during transfer.

3. A welt transfer bar for flat full-fashioned knitting machines, said machines having needles, sinkers, dividers, and knock-over bits for cooperating with said bar during the knitting of a stocking welt, comprising a plurality of long hook elements for engaging alternate loops of the first two courses of said welt, and a plurality of alternately spaced short hook elements for engaging the remaining loops of the first course, whereby said long hook elements will hold the loops of a plurality of courses during transfer and the short hook elements hold the loops of only one course.

4. A welt transfer bar for flat full-fashioned knitting machines, said machines having needles,

sinkers, and knock-over bits for cooperating with said bar during the knitting of a stocking welt, comprising two sets of hook elements comprising a plurality of long hook elements for engaging alternate loops of the first two courses of said welt, and a plurality of alternately spaced short hook elements for engaging the remaining loops of the first course, and means associated with the long and short hook elements for expanding the loops on the respective long and short hook elements at different times prior to said loops passing from said elements during a welt transfer operation.

5. A welt transfer bar for flat full-fashioned knitting machines, said machines having needles, sinkers, and knock-over bits for cooperating with said bar during the knitting of a stocking welt, comprising a plurality of alternately spaced long and short hook elements for engaging the initial courses of said welt, said long hook elements extending beyond said short hook elements a distance at least equal to the distance between the first two courses of the stocking welt, whereby each long hook element will have the loops of a plurality of courses thereon and each short hook element will have a single loop of the first course thereon.

6. A welt transfer bar for flat full-fashioned knitting machines, said machines having needles, sinkers, and knock-over bits for cooperating with said bar during the knitting of a stocking welt, comprising a plurality of alternately spaced long and short hook elements for engaging the initial courses of said welt, said long hook elements extending beyond said short hook elements a distance at least equal to the distance between the first two courses of the stocking welt, and means for expanding the loops on each of said hook elements prior to said loops passing from said elements during a welt transfer operation.

7. A welt transfer bar for flat full-fashioned knitting machines, said machines having bearded needles, sinkers, and knock-over bits for cooperating with said bar during the knitting of a stocking welt, comprising a plurality of hook elements for engaging the initial course loops when knitting the welt, a transversely disposed member uniting one end of said elements, each of said elements having an elongated shank for supporting the initial course loops during a transfer, said shank having a longitudinal slot extending therethrough and disposed opposite the hook on said element, whereby the beard of the associated needle can pass through said slot and engage the end of the hook on said element during a transfer, and a loop expanding member disposed on one side of said shank adjacent the end of said hook, whereby the associated loop will be expanded as it slides off said shank onto said needle during a welt transfer operation.

8. That method of joining the initial welt courses of a stocking to a subsequent course which comprises releasably holding alternate sinker loops only of the first two courses, and at the same time releasably holding the remaining sinker loops of the first course, then knitting a plurality of subsequent courses, and then uniting said releasably held loops to the corresponding loops of one of the subsequent courses.

9. A welt transfer element for full-fashioned knitting machines having a plurality of alternately disposed hook members and a plurality of shorter hook members, the hook members having staggered loop expanding portions associated therewith, the long and short hook members be-

ing adapted to receive the initial course of a welt to thereby produce short and long loops thereon respectively so that during a transfer operation, the slack in the long loops will be available to both the long and short hook members.

10. A welt transfer element having a plurality of short and long hook members for engaging the initial course during transfer, means associated with said short hook members for borrowing the slack from the loops on the adjacent long hook members and means associated with said adjacent long hook members for subsequently borrowing the slack on the first-named short hook members during transfer.

15. 11. A welt bar for full-fashioned knitting machines having alternately disposed long and short hook members each having loop retaining elements on the lower end thereof disposed at different levels and onto which the initial courses are knitted, each of the hook members having an enlarged portion disposed above the hooks on the lower ends thereof and at different levels so that during a transfer operation, the slack in the initial course disposed on all of the hooks will be borrowed first by the short hook members, and then by the long hook members to enlarge the loops to permit the needles of the knitting machine to pass through the loops as the welt bar hooks are withdrawn from the stocking.

20. 12. A transfer bar for full-fashioned knitting machines comprising a plurality of long and short elements, each having a hook on its lower end, alternate elements being long and extending farther downwardly than the ends of the other short elements whereby the initial course will be knitted onto the short elements, and the initial and second courses will be knitted onto the long elements, each element having an enlargement on its shank portion so that when the welt bar is inserted over the needles of the knitting machines, the enlargements on the elements will borrow slack from the initial course to expand the loops on all of the elements and while the loops are expanded, thus permitting the needles of the knitting machine to pass therethrough to allow the welt bar hooks to be removed from the expanded loops.

25. 13. A welt bar for full-fashioned knitting machines comprising a plurality of hooked elements, there being two sets of elements alternately disposed throughout the length of the bar, one set of elements being long and the other set being short, the elements having means on their lower ends for engaging and holding the initial courses of a stocking welt, all of the elements having enlargements disposed above and adjacent the loop holding means, the enlargements on one set of elements being disposed at a higher level than on the other set of elements, and the short elements being adapted to receive the initial course 30 of the welt and the longer elements being adapted to receive the initial and second courses of the welt so that when the welt bar is placed in transfer position relative to the knitting needles, and moved downwardly over the knitting needles to transfer the loops to the knitting needles, the enlargements on the short elements will first borrow slack from the initial course in expanding the loops and then the enlargements on the shorter elements will regain said borrowed slack from the initial course to expand the loops on the long elements, and with the loops thus expanded and disposed on the knitting needles, all of the hook elements of the welt bar can be withdrawn through the expanded loops.

14. A welt bar for full-fashioned knitting machines having short welt hooks for receiving the initial course of a stocking welt and having longer hooks for receiving the initial and second course of the welt, each hook element having an enlargement overshadowing the open end of the hooks on the lower ends of the hook elements, whereby during a transfer operation, the loops on the short and long elements will be successively expanded by the enlargements, and when all the loops are expanded and transferred onto the needles of the knitting machines, the welt bar can be entirely removed from the fabric.

15. A welt transfer bar for flat full-fashioned knitting machines, said machines having needles, sinkers, and knock-over bits for cooperating with said bar during the knitting of a stocking welt, comprising a plurality of alternately spaced long and short hook elements for engaging the initial courses of said welt, said long hook elements extending beyond said short hook elements a distance at least equal to the distance between the first two courses of the stocking welt, and a pair of spaced cam projections on the front side and disposed adjacent the throat of each of said long and short hook elements, the space between said

5 projections being adapted to receive the back of a needle, said cam projection being adapted to expand the associated loop beyond the needle beard as said loop slides off said element onto the needle during a welt transfer operation.

16. A welt transfer element comprising an elongated shank having a reversely bent hook on one end thereof, said hook having a point on its upper end, said shank having a loop expanding element disposed on the same edge of the shank as the hook point and above said hook, said loop expanding element having a groove therein which is open at both ends and extending longitudinally of the loop expanding element.

17. That method of joining the initial welt courses of a stocking to a subsequent course employing a transfer bar with alternately spaced long and short yarn engaging elements, the steps in which comprise knitting the initial course and transferring the sinker loops onto all of said elements, knitting the second course and transferring alternate sinker loops onto the long elements only and then interknitting all of the loops on said long and short elements with the corresponding loops of a subsequent course.

OTTO F. SMETANA.
